UNITED STATES PATENT OFFICE.

DAVID WEISZ, OF NEW YORK, N. Y.

UMBRELLA COVER AND GARMENT.

Application filed August 11, 1926. Serial No. 128,691.

The present invention is concerned with the provision of a unique type of garment adapted to be worn by bathers while walking through the streets, and adapted to serve 5 as an umbrella cover when not in use as a garment.

In many towns along the seashore there are city ordinances which compel bathers to wear some sort of an outer garment over 10 their bathing suits when traveling between the beach and their homes or hotels. It is frequently inconvenient or undesirable to carry a wrap, and the present invention provides a garment which will satisfy the law 15 requiring the covering of the bathing suit, and which may be conveniently used as an umbrella cover when not being worn.

An object of the invention is to provide 20 a device of this character which may be quickly attached to, or detached from an umbrella frame, and which may be quickly donned or doffed when serving as a garment.

Further objects of the invention are to 25 provide a combined umbrella cover and garment of simple, practical construction, which will be neat and attractive in appearance, and which is well suited to the requirements of economical manufacture.

With the above noted and other objects in 30 view, the invention consists in certain novel features of construction and combinations and arrangements of parts, as will be more fully hereinafter set forth and pointed out in the claims. The invention may be more 35 fully understood from the following description in connection with the accompanying drawings, wherein—

Fig. 1 is a plan view showing the device 40 in use as an umbrella cover with part of the fabric which constitutes the cover, broken away to expose the portion of the garment which is folded between the cover and the ribs of the umbrella.

Fig. 2 is a vertical sectional view on the line 2—2 of Fig. 1.

Fig. 3 is an enlarged transverse sectional detail on the line 3—3 of Fig. 1.

Fig. 4 is a fragmentary elevational view 50 of one corner of the interior of the cover showing the manner in which it is secured to the end of a rib.

Fig. 5 is a perspective view illustrating the garment in use.

Fig. 6 is a similar view of the garment.

Fig. 7 is an enlarged detail view showing

the manner of attaching the flange member to the tip of the umbrella.

Fig. 8 is a sectional view through the umbrella tip showing the manner in which the cover is secured adjacent the tip.

60

It is to be understood at the outset that the garment itself may assume many forms; it being preferred to provide a garment in which the skirt portion serves as an umbrella cover, and in which the body-encircling portion is folded within the cover and lies between the cover and the ribs of an umbrella when not in use. This body-encircling portion may merely serve to cover the shoulders and breast of a wearer, or may be 70 in the nature of a relatively capacious cloak which will fall from the shoulder. As a matter of fact, an infinite number of expedients might be resorted to in the matter of designing that portion of the garment 75 which lies under the cover. The style of the garment will be dictated primarily by the requirements of the trade.

As best seen in Figs. 5 and 6 the garment 80 includes a skirt portion 10 adapted to serve as the cover of an umbrella and formed with a contractile waistband 11. Connected to the waistband as by straps 12 is a shoulder covering portion including a front section 13 and a rear section 14 cooperatively defining a neck opening 15.

The manner in which the skirt portion of the garment is used as an umbrella cover may best be seen in Figs. 1 to 4 of the drawings. It will be noted that the bottom 90 of the skirt portion is scalloped or similarly shaped so that it will conform to the ordinary peripheral shape of an umbrella cover. At each of the corners of the lower edge of the skirt, designated by the numeral 16, there are pockets 17 sewed to the inside of the garment and adapted to receive the ends of umbrella ribs 18. Obviously it is necessary that a portion of the skirt be folded inwardly if the umbrella 95 cover is to fit tautly and snugly over the frame, otherwise there would be too great a fullness at the center of the cover.

Having this in view, I attach rows of snap fastener elements or similar separable securing devices 19 to each side of the garment, the two rows of each side being spaced the proper distance apart, so that the material between them can be folded inwardly against the umbrella frame, and the snap fasteners 105 110

joined together as shown in Fig. 1 to stretch the material tautly over the frame. After the ends of the ribs 18 are entered into the pockets 17, the two rows of snap fasteners 5 are brought together and united, it being understood that the shoulder portion 13, 14 of the garment and the straps 12 are folded inwardly through the open waistband before the last snap fasteners are brought 10 together.

As seen in Figs. 1 and 2, the folded shoulder portion of the garment lies between the cover and the ribs. Fig. 3 illustrates the manner in which the inwardly folded portions of the skirt 10 lie against one of the ribs 18 and are concealed from view by closing the snap fasteners 19. It will be understood that the upper portion of the skirt adjacent the waistband is also concealed 15 under the umbrella cover, lying between the cover and ribs as best shown in Fig. 2.

Hooks and eyes 21 and 22 attached to spaced portions of the skirt 10 are connected together closely adjacent the umbrella tip 23, and may be concealed by a covering flange 24 slipped over the tip and over a spring detent 25.

It is believed that the operation of the device will be understood from the foregoing description, but it may be briefly summarized as follows. In applying the garment to the umbrella, the ends of the ribs 18 are slipped into the pockets 17. The shoulder portion 13, 14 and the straps 12 are folded 20 inwardly through the waistband, the waistband being also turned under around the umbrella tip 23. Snap fasteners 19 and hooks and eyes are then secured together, and the covering flange 24 slipped on over 25 the tip or ferrule of the umbrella.

Obviously, various changes and alterations might be made in the general form and arrangement of parts described without departing from the invention. Hence I do 30 not wish to limit myself to the details set forth, but shall consider myself at liberty to make such changes and alterations as fairly fall within the spirit and scope of the appended claims.

50 I claim:

1. A garment including a skirt portion, means on said skirt portion engageable with

the ends of the ribs of an umbrella frame, and means for securing the body of the skirt in properly folded position to serve as a 55 cover for such frame.

2. A garment including a skirt portion, devices spaced along the lower edges of the skirt for engagement with the ends of the ribs of an umbrella and means for folding 60 portions of the body of the skirt inwardly and retaining them folded so that the skirt will constitute a tautly fitting umbrella cover.

3. A garment including a skirt portion, 65 devices spaced along the lower edges of the skirt for engagement with the ends of the ribs of an umbrella and means for folding portions of the body of the skirt inwardly and retaining them folded so that the skirt 70 will constitute a tautly fitting umbrella cover, said skirt carrying spaced rows of 75 detachable fastener elements constituting said means adapted to be secured together with the material of the skirt between them folded under and inwardly against the ribs of the umbrella.

4. A garment including a skirt portion, devices spaced along the lower edges of the skirt for engagement with the ends of the 80 ribs of an umbrella and means for folding portions of the body of the skirt inwardly and retaining them folded so that the skirt will constitute a tautly fitting umbrella cover, said skirt carrying spaced rows of 85 detachable fastener elements constituting said means adapted to be secured together with the material of the skirt between them folded under and inwardly against the ribs of the umbrella, said garment also including 90 a body portion adapted to be folded inwardly through the waistband of the skirt and to lie between said skirt and the umbrella frame.

5. A device as set forth in claim 3, where- 95 in a flange member detachably locked on the ferrule of the umbrella conceals the innermost of the separable fastener elements.

6. A device as set forth in claim 3, and wherein the waistband of the skirt and the material adjacent thereto is also folded 100 under and concealed by the umbrella frame-covering portion.

DAVID WEISZ.
